UNITED STATES PATENT OFFICE.

WILLIAM SCOTT, OF MALDEN, MASSACHUSETTS.

CAR-COUPING.

SPECIFICATION forming part of Letters Patent No. 252,809, dated January 24, 1882.

Application filed April 19, 1881. (No model.)

To all whom it may concern:

Be it known that I, WILLIAM SCOTT, of Malden, in the county of Middlesex and State of Massachusetts, have invented certain new and useful Improvements in Car-Couplings, of which the following is a full, clear, and exact description.

This invention relates to car-couplings of that class provided with hook-shaped coupling devices arranged to rotate or turn against a spring or weight, and thus to be interlocked with and disengaged from each other.

As to such class of couplings, this invention consists principally in the construction of the draw-head and draw-bar in two parts arranged together for the head to swivel upon the draw-bar, which is rigidly fastened in any suitable manner to the under side of the car, all substantially as hereinafter described, reference being had to the accompanying drawings, in which—

Figure 1 is a side elevation of two draw-bars and draw-heads in line with each other, but not coupled together; Fig. 2, a plan view of same with part in longitudinal section; Fig. 3, in one part a side view, and in the other part a plan view, of the draw-heads coupled together; Fig. 4, a face view of the coupling and of a draw-head; Fig. 5, a section on line xx , Fig. 3; Fig. 6, a plan view of the under side of one draw-bar; and Fig. 7, a side view of same, showing its construction for the reception of an ordinary shackling-pin with the ordinary shackling-link.

In the drawings, A A' represent two draw-bars, each to be attached to a car in the ordinary manner; B B', the draw-heads to the draw-bars A A', respectively. These draw-heads constitute the coupling devices proper, and they are constructed and arranged as follows: Each draw-head is swiveled upon the end of its draw-bar so as to freely turn or revolve thereon, and yet be held from escape or detachment—as, for instance, by and through a shouldered pin, a, of the draw-bar and a shouldered socket, b, of the draw-head, (see Fig. 2,) or vice versa.

C is a bent spring, at one end fixed to the draw-bar and at the other and free end, d, interlocked with a notch, e, in the end of the draw-head which is toward the draw-bar. This spring C is protected on each side by a flange

shown as on the one side thereof at n' in Fig. 1 and as on both sides thereof at $n\ n'$ in Fig. 6. The turning or rotation of the draw-head in the one direction is against this spring C and in the other direction with its reaction, and obviously a coiled or spiral spring in lieu of a bent spring may be readily applied and secure the same effect.

Each draw-head is provided with two hooks, D D', of similar shape. These hooks are arranged in position diametrically opposite, or substantially so, and each hook of each draw-head has a shoulder or abutment, f f', which shoulders as to the hooks of each draw-head project in opposite directions, and from such shoulders each hook at its forward part has a curved or cam-shaped end face, g g', which faces as to the two hooks of each draw-head run in opposite directions, and within or beyond the shoulders or abutments of the hooks each hook has a shape, as shown at $h\ h'$ in the drawings, to receive the forward part, l l', of the corresponding hook of the draw-head on the adjoining car, and to allow an interlock between the abutments or shoulders f f' of such hooks when the same are brought together.

In bringing together cars provided with the coupling described the cam-shaped faces g g' of the upper and of the lower coupling-hooks respectively abut against each other, and under such abutment the draw-heads are rotated upon their respective draw-bars, but in opposite directions, and in this case each against their spring C until by the continued movement of the cars toward each other the hooks of the one car pass by and into the space or opening E between the hooks and abut against the draw-head of the other car, and thus they are severally brought into position under the reaction of their springs to be interlocked at their shoulders or abutments f f', the upper hooks and the lower hooks respectively with each other, which secures the coupling together of the two cars, all as is obvious without further description.

To uncouple cars coupled together as above described, it is only necessary to rotate or turn either one or the other of the swiveled draw-heads against their spring sufficient to place the hooks of such draw-head out of interlock with the hooks of the other draw-head, which brings them into the space or opening E be-

tween the hooks of the other draw-head, and thus into a position to allow the cars to be drawn apart without interference between the hooks of their respective draw-heads, when, on 5 then releasing the draw-heads by the reaction of their spring C, they will return to their normal position to be again coupled together. For convenience in so operating the draw-heads, each draw-head is provided with a handle-lever, F, with which is connected one end of a chain, G, secured at its other end at or near the top of the car, and thus in the uncoupling of cars the coupling can be operated as readily and easily from the top of the car as from the 15 ground.

Cars coupled together as above described are secure against detachment in running as the throw of the cars in any direction, either upward or downward, or to the right or left, is 20 resisted in each case by the abutment of the hook or hooks of the one draw-head against the hook or hooks of the other draw-head—as for instance, in the upward throw of a car the upper side of its lower hook strikes against the 25 under side of the upper hook of the adjoining car. Again, in the downward throw of a car the under side of the upper hook abuts against the upper side of the lower hook of the adjoining car; and again in a throw sidewise of 30 either car the separation of the hooks of the two cars is prevented by the side abutments of the hooks of the one against those of the other and in opposite directions.

The swiveling of the draw head to the draw-bar, as above described, is applicable as well to draw-bars provided with a single coupling-hook in lieu of two, as herein particularly shown, and obviously a rotary coupling made for the coupling-head to rotate or swivel upon the 35 draw-bar will be practically free from a bind of the parts, is cheap, is easily made and adapted, and is effective in operation.

In Figs. 2, 6, and 7 the coupling-hooks D D' are shown as each provided with a hole, m, through 40 or in their thickness, which holes are in line with each other, and thus this coupling is adapted to receive the shackling-pin of a car-coupling having a shackling-link, H, should occasion require the coupling of such a car with a 45

car having a coupling of the present improved 50 form, all as shown in Fig. 7 more particularly. This feature is also adaptable to couplings of this class having only one coupling-hook, in which case it would be only necessary to provide a rest of some kind for the link and lower 55 end of the pin.

More than two coupling-hooks for each draw-head may be employed, if so desired, but two are sufficient to secure the safety of the parts of the coupling from accidental detachment 60 and escape.

In lieu of using springs for the return of the coupling-hooks, as described, weights may be employed; but springs are obviously preferable.

I am aware that a car-coupling composed of a 65 coupling-hook which is at the end of a draw-bar arranged upon the car to turn in bearings thereof is not new; adapted to rotate or turn is not new; and that also it is not new to combine therewith a bumper for the abutment of the 70 end of the coupling-hooks upon the adjoining cars when two cars are brought together to be coupled.

Having thus described my invention, what I claim, and desire to secure by Letters Patent, 75 is—

1. A rotary car-coupling composed of a stationary draw-bar, A, and of a head, B, which is swiveled to the draw-bar and is provided with one or more cam-shaped hooks, D, in combination with a spring or weight, constructed and arranged together, to operate substantially 80 as described.

2. A rotary car-coupling composed of a stationary draw-bar, A, and of a draw-head, B, 85 which is swiveled to the draw-bar and is provided with one or more cam-shaped hooks, D, in combination with a bent spring, C, attached to the draw-head and draw-bar and protected on each side by flanges n n' of the draw-bar, 90 all substantially as described.

In testimony whereof I have hereunto set my hand in the presence of two subscribing witnesses.

WILLIAM SCOTT.
